INVENTOR

Charles N. Coryell

BY

Albert W. Austin

ATTORNEY

UNITED STATES PATENT OFFICE.

CHARLES N. CORYELL, OF NEW YORK, N. Y.

VANITY CASE

Application filed February 8, 1923. Serial No. 617,807.

To all whom it may concern:

Be it known that I, CHARLES N. CORYELL, a citizen of the United States, and resident of New York city, in the county of New York and State of New York, have invented certain new and useful Improvements in Vanity Cases, of which the following is a specification.

This invention relates generally to metallic receptacles, boxes or cases for holding several different articles, and relates particularly to small compact and ornamental cases or boxes, such as vanity cases, that are frequently made of or coated with precious metals.

The improvement relates broadly to such a case or box provided with means for holding one or more articles in removable spaced trays or receivers and holding at least one article wholly or partly concealed from view in a separate compartment.

The invention also relates to the compact arrangement of the separate trays and compartments of the case or box in a narrow shallow case permitting each article contained in the case and the special trays or receivers therefor to be independently accessible and removable without disturbing any of the others.

The invention further and more specifically relates to the construction of the trays, containers or receivers so as to permit the easy insertion and removal of a false bottom that may be integral with or attached to the article supplied to such trays or receiver.

Various other objects and advantages of the invention will be in part obvious from an inspection of the accompanying drawings and in part will be more fully set forth in the following particular description of one form of device embodying my invention, and the invention also consists in certain new and novel features of construction and combination of parts hereinafter set forth and claimed.

In the accompanying drawings the invention is shown embodied in a vanity case comprising a plurality of trays to receive powders or similar toilet articles and a separate holder for another toilet article, such as a paste stick or filler. In said drawings:

Fig. 1 is a view in perspective of a vanity case embodying my invention with the cover closed.

Fig. 2 is a plan view of the same with the cover open.

Fig. 3 is a longitudinal section of the case on the line 3—3 of Fig. 1.

Fig. 4 is a view of the case showing the mirror.

Fig. 5 is a transverse view of the case with the cover closed.

Fig. 6 is a perspective view of one of the removable trays.

Fig. 7 is a perspective view of the plate. 65

The case illustrated in the drawings comprises the two dished lids or cover sections 1, preferably provided with narrow side flanges that are hinged as at 2, and are closed by a suitable snap 3. The cover sections may be of any preferred configuration, and may be provided with a bezel 4, but such bezel may be omitted if desired. 70

A frame 5 is mounted on one of the cover sections and comprises supporting side flanges 6 that seat within the cover, and a plate or platen 7 that extends across and over a portion of the cover section at a level somewhat above the up-turned side flanges of the cover. The frame may be secured 80 in place in any suitable manner, as by being soldered to the cover section, or it may be removably held in place by being snapped into position and retained by the resiliency of the flanges. The other cover section has 85 a mirror 8 mounted thereon by any suitable means, as the projections 9, engaging under the bezel.

The frame is provided with openings 10 of any preferred shape to receive the removable tray or article container 11. This tray may seat on the case section or may be supported from the frame. The upper part of the tray extends above the plate and is provided with means engaging the top of the 95 plate whereby it may be lifted from the frame, such as an outwardly extending lug or rib 12. Below the plate and at or near its bottom the tray is provided with an inwardly extending ledge or flange 14 to support a removable or false bottom 15. The sides of the tray are formed with one or more resilient snaps 16 formed integral with the tray by stamping out metal, which retain the bottom in place and prevent rattling thereof, but which permit the same to be removed when the tray is taken out of the case and a suitable amount of pressure is applied to the bottom to force the same out of engagement. 100

Mounted upon the frame below the plate or platen is a supporting holder 17, accessi- 110

ble from the exterior of the frame through the opening 18 provided in the side flange of the frame. This holder, which may be in the form of a trough or sleeve, projects inwardly toward the opposite flange of the frame, and receives and supports an article, such as a paste filler or crayon 19, beneath the plate so that it will be concealed when the case is open. The paste or crayon may be of any standard commercial size and shape, and such articles are usually supplied with a metallic envelope or cartridge 20 having a projecting knob 21 which moves the paste filler or crayon in the metal sheath. This knob engages in a slot 22 provided in the top of the plate, and affords a means for removing the crayon from the holder 17 whenever it is desired to use the same. It is not necessary to use the outer cap or jacket usually supplied with pastes and crayons of this character, since the plate in conjunction with the cover section forms an article-receiving compartment that encases and protects the crayon. Owing to the small size and light weight of the crayon the holder need not extend entirely across the case, but if any other article is used the length of the holder can be made to correspond therewith. Preferably the holder is of such shape that the cartridge will be held snugly in its adjusted position.

A portion of the case section 23 is cut away opposite the opening 18 to permit the removal of the crayon cartridge. The opposite cover section is provided with a lip or extension 24 which engages in this recess to close the same when the case is closed.

The trays or receivers illustrated in the drawings, are designed to hold a toilet article, such as a powder or rouge compact that is sold usually with a glass or similar base, on which the powder or rouge is compacted, and this glass or other supporting base constitutes the removable bottom of the tray. The tray may easily be taken out of the frame by grasping the projecting rib or lip thereof which is above the plate, and when the tray is removed, the bottom of the powder compact which also constitutes the false bottom of the tray can be forced out by a slight pressure to overcome the resiliency of the spring snaps, whereupon a fresh compact can be inserted as a unit.

By means of this construction I provide a thin, light and very compact case. These features are especially desirable in an article of this class that is sometimes used as an ornament and is frequently carried about by the owner. The case comprises in effect three compartments, two of which are provided by the removable trays, the contents of which are visible and accessible when the case is opened, and the other is formed between the plate and the case section, the contents of which are concealed and inac-

cessible except by withdrawing the article from the holder.

The end of the metal sheath, envelope or cartridge for the crayon or other article within the closed compartment is utilized in the present construction to give a finish to the case, but it is evident that the shape of the metal sheath or cartridge is immaterial, since the opening through the side flange of the frame can be changed as desired. The trays may be round or any other shape, and preferably project to a greater or less extent above the level of the frame, but if it should be considered desirable to secure the tray permanently to the frame in order to meet any special demand, this may be accomplished by soldering it in place, or securing it in any other well-known manner. It will also be apparent that one of the trays can be omitted, and the case correspondingly shortened, or that the compartment may be shifted with respect to the trays.

While I have shown and described and have pointed out in the annexed claims certain novel features of my invention, it will be understood that various omissions, substitutions and changes in the form and details of the device illustrated and in its operation may be made by those skilled in the art without departing from the spirit of my invention.

Having thus described my invention, I claim:

1. In a vanity case, the combination of hinged cover sections, one of said sections having an inwardly projecting flange, a frame comprising a relatively rigid top plate with an integral, resilient, dependent peripheral flange seating in the flanged cover section and engaged with the flange of said section intermediate the top plate and the lower edge of the dependent flange thereby to utilize the resiliency of said dependent flange for securing the frame in place and to support the top plate above the rim of the cover section with an article receiving space beneath the same, and said top plate having an opening for seating a compact or the like.

2. In a case of the character described, comprising hinged cover sections, a frame seated in one of said cover sections and removable therefrom, and an article-container removably mounted in said frame, said container being provided with a removable bottom and with a spring catch engaging said bottom and normally holding the same in contact with the container and permitting the removal thereof.

3. In a compartment case, the combination with a plurality of removable compartments comprising article-receiving trays, of a frame secured to one of the case sections and engaging with said removable trays nor-

- 5 mally to hold the same in spaced relation, said frame comprising a plate section spaced from the cover to form a stationary compartment, and means to hold a separate article in said compartment below the plate thereby to conceal the same when the case is open.
4. In a case of the character described comprising hinged cover sections, the combination with one of said cover sections, of a frame comprising a plate section spaced from the cover section, a removable article-receiver held against lateral displacement by said frame, and means below the plate section to hold a separate article and conceal the same beneath the plate.
5. A box or case comprising dished and hinged cover sections, a frame mounted on one of said cover sections consisting of a side flange projecting above the edge of said cover section and a plate integral with the side flange spaced from the cover section to form a compartment therewith, said side flange being provided with an opening into said compartment, means adjacent said opening to secure a removable article within said compartment, and an article-receiving tray seating within said compartment and extending above the plate.
- 30 6. A case, having dished cover sections hinged at one edge and closed by a catch at the other edge, a frame mounted on one of said cover sections comprising a flanged plate spaced from the cover section to form a compartment and provided with an opening through the flange into said compartment, means within said compartment to receive a removable article, said cover section having a recess in its side to register with said opening in the frame, and means on the other cover section to engage in said recess when the case is closed.
7. The combination of a case having dished cover sections hinged at one edge, a frame mounted on one of said cover sections comprising a flanged plate spaced from the cover section to form a compartment and provided with an opening through the flange into said compartment and with a slot above the opening, an article-holder within the compartment adjacent the opening, and an article in said holder provided with a projecting knob engaging in said slot.
- 55 8. A case to contain a plurality of articles comprising dished cover sections having a hinged connection so as to be closed together, an article-receiver, a stationary plate supported on one of the cover sections engaging said receiver to position the same relative to the cover section, and a holder for a separate article mounted below the plate so that said article will be concealed by the plate.
9. A case to contain a plurality of articles having dished cover sections hinged at one edge, a frame mounted on one of said cover sections comprising a flanged plate spaced from the cover section to form a compartment and provided with an opening through the flange into said compartment and with a slot above the opening, an article-holder within the compartment adjacent the opening, an article in said holder provided with a projecting knob engaging in said slot to position the same relative to the cover section, and a plurality of removable trays seating within the compartment and projecting above the plate.
10. A case to contain a plurality of different articles comprising dished cover sections having a hinged connection so as to permit said sections to be brought together in closed position, a plurality of removable article-receivers, a stationary plate supported above one of the cover sections by flanged sides secured to said cover section and engaging said receivers to position the same and permit access thereto from above the plate, and a holder for a separate article mounted below the plate and concealed thereby and communicating with an opening provided in the side of the plate whereby said article may be removed from the compartment.
11. In a vanity case having hinged cover sections, the combination with one of said cover sections, of a frame comprising an article holding top plate and a peripheral flange resiliently engaging said cover section to space the top plate from the wall of said cover section and thereby form an article receiving space between said top plate and said cover section, and means below the top plate to hold a separate article concealed in said space beneath the top plate.

Signed at New York, in the county of New York and State of New York, this 3rd day of February, A. D. 1923.

CHARLES N. CORYELL.
